US0D1059173S

(12) **United States Design Patent** (10) **Patent No.:** **US D1,059,173 S**
(45) **Date of Patent:** **** Jan. 28, 2025**

(54) **JAR WITH CAP**

(71) Applicant: **Greenlane Holdings, LLC**, Boca Raton, FL (US)

(72) Inventors: **Shane Grant Blomberg**, Hermosa Beach, CA (US); **Edward Kilduff**, Hermosa Beach, CA (US)

(**) Term: **15 Years**

(21) Appl. No.: **29/768,152**

(22) Filed: **Jan. 27, 2021**

Related U.S. Application Data

(63) Continuation of application No. 29/683,123, filed on Mar. 11, 2019, now Pat. No. Des. 909,207, which is a continuation of application No. 29/670,346, filed on Nov. 15, 2018, now Pat. No. Des. 918,040, which is a continuation-in-part of application No. 29/589,016, filed on Dec. 27, 2016, now Pat. No. Des. 842,700, which is a continuation-in-part of application No. 29/580,322, filed on Oct. 7, 2016, now abandoned.
